UNITED STATES PATENT OFFICE.

HERBERT JACOBSEN, OF BROWNSVILLE, TEXAS.

HAIR-PIN.

1,068,244.

Specification of Letters Patent. Patented July 22, 1913.

Application filed May 5, 1911. Serial No. 625,128.

To all whom it may concern:

Be it known that I, HERBERT JACOBSEN, a citizen of Denmark, and a resident of Brownsville, in the county of Cameron and State of Texas, have invented a new and Improved Hair-Pin, of which the following is a full, clear, and exact description.

This invention relates to a new and improved hairpin of a type adapted to automatically secure itself in position on the hair.

It has been found in the ordinary hairpin of the bifurcated type, that when not securely placed in the hair, it is very likely to jar or slip out and get lost. This is exceedingly disagreeable, especially if the hairpin is of considerable value.

It is therefore an object of this invention to provide means on the hairpin itself which will automatically engage a portion of the hair and grip the same, so as to secure the hairpin in position on the hair without danger of getting lost. This and further objects, together with the construction and combination of parts, will be more fully described hereinafter and particularly set forth in the claim.

Reference is to be had to the accompanying drawings forming a part of this specification, in which similar characters of reference indicate corresponding parts in all the views, and in which—

Figure 1 is a perspective view of one form of my device; Fig. 2 is a longitudinal section through the form shown in Fig. 1; Fig. 3 is an extended view of the blank from which another form of my device is made; Fig. 4 is a side view in elevation of the second form of my device; and Fig. 5 is a top edge view of the form shown in Figs. 3 and 4.

Referring more particularly to the separate parts of this invention as embodied in the forms shown in the drawings, it will be seen that in Figs. 1 and 2 is illustrated a comb 1 of the bifurcated type, having tines 3, the inner edges of which converge toward each other from the outer point of the tines toward the points of their connection, where by the tines will be somewhat tapering, thereby permitting them to be readily inserted in the hair.

For the purpose of securing the pin in position in the hair, there is provided a gripping construction, which in the form illus-

trated in Figs. 1 and 2 is shown as embodying a supplementary bifurcated locking member 4, having spring tines 5 and 6 corresponding to the tines 3 and adapted to cooperate therewith to grip a portion of the hair between the contacting surfaces and entrap the same, so as to secure the pin in position in the hair. It will be noted in this form that the spring tines 5 and 6 are arched at 7, in one direction, and at 8 in the opposite direction, so that the ends of the spring tines, indicated at 9, diverge away from the tines 3, whereby the hair can readily enter between the tines 3 and the tines 5 and 6.

In the form shown in Figs. 1 and 2, the hair-entrapping or locking member 4 is shown as comprising a single sheet of metal secured in any well known manner to the body of the hairpin 1, as by means of rivets 10 passing through alined openings in the hairpin and the member 4, and also by providing a tongue 11 on the member 4, which is bent or flexed around the bridge or arch of the pin 1, so as to grip opposite faces of the pin, and thus further secure the locking member 4 to the pin.

In the form shown in Figs. 3, 4 and 5, the hair-entrapping or locking member 4 is shown as being formed integral with the pin 1, and bent over, as clearly illustrated in Fig. 5, so that the tines thereof correspond to the tines on the pin and coöperate therewith to entrap a sufficient quantity of hair to lock the pin in position in the hair. Otherwise this pin conforms to the form shown in Figs. 1 and 2.

It will thus be seen that there is provided a simple and efficient hairpin, which can be readily inserted in the hair, and when once inserted, will grip a portion of the hair, so that it cannot be shaken out or lost in any way whatsoever.

While I have shown two embodiments of my invention, I do not wish to be limited to the specific details thereof, but desire to be protected in various changes, alterations and modifications which may come within the scope of the appended claim.

Having thus described my invention, I claim as new and desire to secure by Letters Patent:—

The combination with a hairpin, bifurcated to form a pair of tines secured integrally together, of a resilient hair-locking or entrapping member bifurcated to form a

pair of tines corresponding to said first-mentioned tines and extending respectively in juxtaposition thereto, said last-mentioned tines being arched at a plurality of points to contact with said first-mentioned tines and to form arched spaces between said first-mentioned and last-mentioned tines adapted to entrap hair, whereby said pin may be secured to a body of hair, the corresponding

tines of each pair coöperating with each other to hold the hair between them.

In testimony whereof I have signed my name to this specification in the presence of two subscribing witnesses.

HERBERT JACOBSEN.
